UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A CHILD'S WRAP.

SPECIFICATION forming part of Design No. 14,831, dated February 28, 1884.

Application filed January 23, 1884. Term of patent 3½ years.

To all whom it may concern:

Be it known that I, MARY TURNER, of the city, county, and State of New York, have invented and produced a new and original Design for a Pattern of a Child's Wrap, (numbered 9,033;) and I do hereby declare that the engraved prints accompanying this specification convey to any one accustomed to using paper patterns a clear understanding of how a garment made up by the pattern will appear.

The design shows loose fronts with buttons all the way down, and exhibiting clustered shirrings at the neck and waist-line; a loose

back also having clustered shirrings at the neck and waist-line; a pointed hood exhibiting gathers at the neck and a frill finish at the back; a standing collar, and coat-sleeves.

What I claim as my invention, and desire to secure by Letters Patent, is—

The design for a child's wrap, as shown in the engraved prints accompanying this specification.

MARY TURNER.
